ATTACHMENT FOR TYPEWRITING MACHINES

John L. Petz, Rochester, N. Y., assignor to International Business Machines Corporation, New York, N. Y., a corporation of New York

Application December 27, 1939, Serial No. 311,094

6 Claims. (Cl. 282—29)

This invention relates to attachments for typewriting machines, particularly, that type of machine known as a continuous billing machine. In this type of machine there is usually provided a forms carrier of some sort having means to anchor a plurality of carbon sheets which are interleaved with continuous forms of either the fanfold or superposed separate web types. The anchoring means for the carbon sheets is usually made movable and provided with an operating means of some sort which enables the carbon sheets to be shifted relative to the forms as soon as one set of the forms has been written so as to transfer the working portions of the carbon sheets to the next set of forms. The carbon sheet anchoring means usually takes the form of a thin blade around which the carbon sheet is folded or looped and held in place by means of one or more clips. These clips take various forms but usually consist of a simple U-shaped member like a paper clip designed to be placed over the loop of carbon paper on the blade so as to clamp the portion of the carbon sheet adjacent the fold close against the sides of the blade.

It is imperative, particularly when fanfolded forms are used, that the carbon sheet be folded around the blade with the line of the fold absolutely square with the longer edges of the carbon sheet. Otherwise, owing to the lengths of these sheets, the working portions may become crumpled or torn in the event the sheets project beyond the edges of the webs or, in case of fanfolded forms, may wrinkle from dragging in the longitudinal creases.

It is very difficult for the operator to fold the carbon sheet square as only a very narrow portion of the carbon sheet is folded around the blade for attachment thereto by means of the clips. Thus, no matter how careful the operator may be to fold the sheet square, it frequently happens that the carbon sheets are skewed when the blades are mounted in the forms carrier. Usually a forms carrier is provided with mounting posts which have means to secure the carbon blades in place and the blades customarily extend at right angles to the path of movement of the forms through the machine. It will be appreciated, therefore, that any slight deviation from squareness at the point of attachment to the machine will result in a very considerable lateral displacement of the leading edges of the carbon sheet as usually the carbon sheets are quite long, it being very common to use carbon sheets 30 inches long.

The primary object of the present invention is to provide a very simple and inexpensive device for use in a continuous billing machine to enable the operator to accurately fold the carbon sheets about the blades and attach them thereto by means of clips. It will be understood that in the present case the specific form of clip used is immaterial but that any of the usual forms of clips now known in the art may be used.

10 Other objects of the invention will be pointed out in the following description and claims and illustrated in the accompanying drawing, which discloses, by way of example, the principle of the invention and the best mode, which has been contemplated, of applying that principle.

In the drawing:

Fig. 1 is a plan view,

Fig. 2 is a side view partly in section.

Fig. 3 is an end view.

20 Fig. 4 is a vertical section on the line 4—4 in Fig. 1 through the carbon sheet.

In the drawing the numeral 10 represents a suitable oblong base plate which may be made of some relatively light, cheap material such as

25 aluminum provided with suitable resilient feet in order to avoid slippage of the device on a smooth surface such as a desk top and also to avoid marring the desk top. These feet conveniently may take the form of rubber buttons 11

30 which are formed with a shouldered portion pressed into suitable holes 10a formed in the base plate 10. Secured along one of the longer edges of the base plate 10, as by means of bolts

12, is a side guide or aligning member which

35 may consist of an angle strip 13. A movable side

guide, consisting of a similar angle strip 14, is

adjustably slidably mounted on the half of the

plate 10 opposite to the strip 13. For this purpose the base plate 10 is provided with three

40 slots 10b which extend at right angles to the

strip 13, that is, parallel to the shorter sides of

the base plate 10, from the upper edge of the

plate 10 (Fig. 1) toward the center of the plate

45 as shown in Fig. 1. Projecting through holes in

side guide 14 are the bolts 15, the heads of which

are slightly under cut, as best shown at the left

50 in Fig. 2, to loosely fit the slots 10b and prevent

the bolts from turning when wing nuts 16 on

the bolts are turned to clamp the side guide 14

55 in adjusted position. The side guide 14 may be

adjusted toward or away from the side guide 13

to accommodate the width of the carbon sheet

S which is to be attached to a carbon sheet

anchoring blade.

55 For the purpose of yieldingly holding the car-

bon sheet against accidental movement, there is provided clamping means which is not positive in its nature but permits the sheet S to be drawn through the guides 13 and 14 by the exertion of a certain amount of tension applied at one end of the sheet by the operator's hand. This clamping means in part includes a rod 17 which is inserted into diagonal slots 13a, 14a (Figs. 1 and 2) formed in the side guides 13 and 14. These slots have a vertical apron portion to facilitate assembly. Adjustably slidably mounted on the rod 17 are rollers 18 of a type commonly used on the paper balls of typewriting machines for the purpose of holding the work sheets in firm contact with the platen above the writing line. In order to prevent the rod 17 from being readily withdrawn from the slots 13a, 14a by a lengthwise movement of the rod, the ends of the rod are provided with suitable caps 17a. Each of the side guides 13, 14 is provided with a leaf spring 19 which may be fastened to the side guides by welding or riveting and is curved as shown in Fig. 2 to urge the rod 17 toward the closed ends of the slots 13a, 14a so as to exert pressure on the carbon sheet S located between the side guides.

The rollers 18 not only are capable of turning on the rod 17, but also may be slid along the rod so as to be settable equal distances from the edges of the carbon sheet to prevent the carbon sheet from skewing when the sheet is adjusted lengthwise of the guides 13, 14 to obtain the proper amount of loop about the carbon blade. The springs 19 exert sufficient pressure on the ends of the rod 17 to produce enough friction between the ends of the rod 17 and the springs 19, between the rod and the edges of the slots 13a, 14a, and between the parts of the rollers 18 and the rod 17, to require exertion of a small amount of tension on the end of the carbon sheet to draw the carbon sheet through the guides 13, 14, but the friction is not great enough to cause the sheet to be torn in manipulating it to get the proper length of loop.

The right-hand ends of the side guides 13, 14 are provided with open horizontal slots like 13b (Fig. 2) to loosely receive the carbon blade 20. The latter, in the present case, is shown as consisting of a thin flat strip of metal and is usually made of a light metal like aluminum. Since the carbon sheets must be not only square with the blade 20, but must also be located at a predetermined distance from one end of the blade, adjustable stop means is provided to locate the carbon blade in the slots 13b. This stop means consists of an L-shaped wire bracket 21 having one of its arms formed with a U-shaped loop straddling a bolt 22 attached to the end of the side guide 14. The other arm of the bracket 21 extends at right angles to the vertical face of the side guide 14, parallel with the underside of one end of the blade 20, and is provided with an adjustable collar 23 against which the end of the blade 20 may be positioned as shown in Figs. 1 and 3 to determine the position of the carbon sheet on the blade.

The carbon sheet clip is shown in plan view in Fig. 1 and in section in Fig. 4 and is generally designated 24 in these views. The clip 24 consists of two identical formed members 24a which may consist of sheet metal stampings which are secured to a central filler strip 25 (Figs. 1 and 4) designed to press the edge of the crease in the carbon sheet against one edge of the blade 20. This strip 25 serves three purposes, one of

which is to prevent spreading of the sides of the clip by entry of the blade 20 into the clip. The other purposes are to prevent tearing the carbon sheet on the edges of the blade and to insure that the web guide portions 24a of the members 24 will be at right angles to the blade 20. The web guide portions 24a are secured together and are designed to ride on the inside of the fold along the longitudinal edges of the fanfold 10 forms in the billing machine and guide the fold to a web splitting portion 25a (Fig. 1) formed in the end of strip 25. The edges of the members 24 are flared slightly at 24b (Fig. 4) to enable the clip to be more easily slipped over the fold of the carbon sheet and the members are formed to evenly press to the sides of the blade the portions of the carbon sheet against the fold, as shown in Fig. 4.

Assuming that the side guide 14 has been adjusted to the width of the carbon sheet S, the latter is placed between the side guides 13, 14 by slightly raising the rod 17 against the tension of springs 19 and slipping the carbon sheet underneath the rollers 18. The carbon blade 20 is now inserted in slots 13b. The carbon sheet is next adjusted lengthwise of the side guides 13, 14 until the right-hand end of the sheet extends the proper distance to the right of the right-hand edge of the blade 20 and folded about the blade. The clip 24 is now pressed over the loop formed in the carbon sheet and the operation is completed by removing the sheet with the blade attached thereto from the device by releasing the pressure of the rollers 18 and slipping the blade with the attached carbon sheet out of the slots 13b. Owing to the fact that the slots 13a, 14a are inclined at an angle to the top surface of the base 10, it is possible to release the pressure of the rollers 18 by pressing the rod 17 to the left at a point near its middle far enough to raise the rollers 18 out of contact with the carbon sheets.

While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In an attachment for typewriting machines, a base plate, a fixed side guide mounted along one edge of said base plate and cooperating with one edge of a sheet of transfer material which is to be attached to an anchoring member, a second side guide extending parallel with the first guide and cooperating with the opposite edge of the sheet of transfer material, means to movably mount one of said guides on said base plate to accommodate sheets of transfer material having various widths, means adjustably movably supported on both guides for holding the sheet against movement longitudinally of the side guides when the sheet is in position therebetween, and means to mount the member to which the carbon sheet is to be attached at one end of the side guides and in a predetermined relationship to the sheet of transfer material to enable said sheet to be attached to said blade.

2. In an attachment for typewriting machines, a base plate, a fixed side guide mounted along

one edge of said base plate and cooperating with one edge of a sheet of transfer material which is to be attached to an anchoring member, a second side guide extending parallel with the first guide and cooperating with the opposite edge of a sheet of transfer material, means to movably mount said second guide on said base plate to accommodate said attachments to sheets of transfer material having various widths, means movably mounted on both side guides for holding the sheet against movement longitudinally of the side guides when the sheet is in position therebetween, including pressure elements adjustable transversely of the guides; means to mount the member to which the carbon sheet is to be attached at one end of the side guides and in a predetermined relationship to the sheet of transfer material to enable said sheet to be attached to said blade, and means to adjustably locate said blade in the mounting means.

3. An attachment for typewriting machines comprising a base, a pair of aligning members mounted on the base in parallel spaced relationship, one of said aligning members being adjustable with respect to the other to accommodate a transfer sheet therebetween, both of said members being shaped to support on said base a member to which said transfer sheet is to be attached in a predetermined angular relationship to enable said transfer sheet to be secured to said member while held in said relationship by said aligning members, and means having a plurality of adjustable sheet engaging elements for yieldingly holding said transfer sheet in position between said aligning members, said sheet engaging elements being aligned transversely of said aligning members and adjustable relative thereto to grip the transfer sheet equal distances from the opposite edges thereof.

4. In an attachment for typewriting machines, a base forming a table on which a manifolding transfer sheet may be laid; a pair of side guides disposed in parallel spaced relation on said table, each of said side guides being so constructed and arranged at one end to removably loosely support a member to which one end of the transfer

sheet is to be attached by folding a portion of said sheet about said member; means adjustably mounting one of said guides on said base to accommodate transfer sheets of different widths, and stop means for determining the position of the transfer sheet on said member.

5. An attachment for typewriting machines utilizing transfer sheets attached to a transfer sheet supporting member in a predetermined angular relationship, comprising a base forming a table on which the transfer sheet may be laid; a pair of side guides mounted on said base in parallel spaced relation to cooperate with opposite edges of the transfer sheet and hold the latter in a fixed position, both of said side guides being so constructed and arranged as to support the member to which the sheet is to be attached in a predetermined angular relation to the member; a sheet holding device movably supported at both ends by the side guides, and means on the side guides and cooperating with the ends of the sheet holding device to engage said device with said sheet with uniform pressure.

6. An attachment for typewriting machines utilizing transfer sheets attached to a transfer sheet supporting member in a predetermined angular relationship comprising a base forming a table on which the transfer sheet may be laid; a pair of side guides mounted on said base in parallel spaced relation to cooperate with opposite edges of the transfer sheet and hold the latter in a fixed position, both of said side guides being so constructed and arranged as to support the member to which the sheet is to be attached in a predetermined angular relation to the member, a sheet holding device movably supported at both ends by the side guides, and means on the side guides and cooperating with the ends of the sheet holding device to engage said device with said sheet with uniform pressure, said sheet holding device also having sheet engaging elements adjustable transversely of the side guides to position said elements equal distances from the edges of the sheet.

JOHN L. PETZ.
